UNITED STATES PATENT OFFICE.

JOHN A. ZUBLIN, OF LOS ANGELES, CALIFORNIA.

PACKING STRUCTURE AND METHOD OF MAKING SAME.

Application filed February 9, 1923. Serial No. 617,902.

To all whom it may concern:

Be it known that I, JOHN A. ZUBLIN, a citizen of the Republic of Switzerland, residing at Los Angeles, in the county of Los Angeles and State of California, have invented a new and useful Packing Structure and Method of Making Same, of which the following is a specification.

This invention relates to an improved type of packing structure which is particularly adapted for use as a piston or pump plunger packing, and to a method of making same.

The invention has for an object to provide an expansible tubular packing structure which is longitudinally slit to form a series of co-engaging blades or sections with the several slits normally closed and so disposed as to remain closed throughout their length during expansion or contraction of the structure.

Another object is to provide an expansible tubular packing structure which is longitudinally slit from one end inwardly at circularly spaced intervals to form a series of yielding blades, with the slits normally closed and angled transversely in respective planes out of registry with the axis of the structure whereby the several blades remain in coengagement during the yielding movements of the structure.

A further object is to provide a method of making a packing structure of the above character.

Various other objects and advantages will be more fully apparent from the following description of the accompanying drawings which form a part of this disclosure, and which illustrate a preferred form of embodiment of the invention.

Of the drawings:

Figure 1 is a central vertical section through a well pump structure with the packing structure of the present invention incorporated therein.

Figure 2 is an elevation of a piece of material longitudinally slit in accordance with the first step in the herein described method.

Figure 3 is a plan section on line 3—3 of Figure 2.

Figure 4 is a section of reduced size and similar to Figure 3, showing the slitting of a piece of material which is normally tubular, instead of solid as in Figure 2.

Figure 5 is an elevation similar to Fig-

ure 2, showing the slits closed in accordance with the second step in the herein described method.

Figure 6 is a plan section on line 6—6 of Figure 5.

Figure 7 is an elevation, partly broken away and in section and looking in the direction of the arrow in Figure 8, illustrating the third step in the herein described method.

Figure 8 is a plan section on line 8—8 of Figure 7.

Figure 9 is an elevation, partly broken away and in section and taken approximately on line 9—9 of Figure 10, illustrating the fourth step in the herein described method.

Figure 10 is a plan section of the finished packing member, taken on line 10—10 of Figure 9.

Figure 11 is an elevation, partly broken away and in section, showing a modified form of packing structure.

Figure 12 is a plan section on line 12—12 of Figure 11.

Figure 13 is a vertical section showing a packing structure of the type to which this invention relates, as applied to an engine piston, and

Figure 14 is a plan section on line 14—14 of Figure 13.

Referring to Figure 1, the packing structure is shown incorporated in a fluid pump in which 1 designates a pump tubing or working barrel in which the pump operates, 90 and 2 designates a usual type of standing valve, the pump comprising a sucker rod section 3 and a garbutt rod pipe 4 joined together by a guide member 5, the pipe 4 being connected to the lower end of the standard 95 sucker rod string 6. The rod section 3 and guide member 5 are bored to receive the garbutt rod 7 which is attached to the standing valve cage, and the upper end of the garbutt rod extends into the garbutt rod 100 pipe 4 and has attached to its upper end a garbutt nut 8. The lower end of the rod section 3 has a valve element 9 which is adapted to cooperate with a valve seat 10 formed at the lower end of the packing 105 structure member 11, which in this instance, constitutes the pump plunger.

This arrangement permits the sucker rod line to have an initial independent movement during which the valve first operates 110 to control the passage of fluid through the plunger, and is then moved to translate the

plunger. In the operation of this type of pump, an initial down stroke of the rod first effects an opening of the valve 9, the guide member 5 then contacting the upper 5 end of the tubular packing structure member 11 and translating it to the end of the down stroke. Upon the up-stroke the initial movement of the rod effects a closing of the valve 9 and upon a continued movement of 10 the rod translates the member 11 in a pumping stroke. The garbutt rod device permits a free pumping stroke and when the pump rod is pulled beyond the pumping stroke in pulling the pump, said device effects a 15 pulling of the standing valve.

This type of pump forms the subject matter of my copending application, Serial Number 610,808, titled "Pump and garbutt device," to which reference may be had for 20 a more detailed illustration and description of the details of construction and operation.

The packing structure to which the present invention relates, comprises the tubular 25 packing member 11 which is longitudinally slit from one end inwardly as indicated at 12 (see particularly Figures 1 and 10) and at circularly spaced intervals to form a series of relatively spaced blades 13 and intermediate blades 13^a cooperating with the spaced 30 blades 13 to maintain a complete circular packing surface.

In certain instances it is desirable to associate with the packing member 11, an inner 35 flexible sealing member 14 which consists of a relatively thin flexible sleeve positioned between an internal shoulder 15 and an internal shoulder 16 located below the lower ends of the several slits 12. This 40 sleeve 14 is preferably formed of a flat piece of sheet metal rolled upon itself with its free edges overlapping, and provides a sealing member capable of expanding under the influence of the pressure of the liquid within 45 the pump plunger and will in turn press outwardly the several blades 13—13^a, whereby said blades engage the walls of the pump tubing with a pressure which will 50 vary with the pressure of the fluid packed against.

As plainly shown in Figures 1 to 10 the packing member 11 is slit to provide six cooperating blades with each slit transversely angled relative to its radial disposition, that is, the transverse plane of each slit is 55 out of registry with the axis of the packing structure as a whole. In other words, the transverse plane of each slit is to one side of said axis as distinguished from a 60 plane which intersects said axis.

It will be noted that the successive slits are reversely angled and that each longitudinal edge of the several blades correspond to that of the co-engaging edge of 65 the adjacent blade so that during the ex-

panding or collapsing of the structure said longitudinal edges will slide upon each other without causing a separation of the slits.

While the structure illustrated in Figures 1 to 10 is slit to provide six blades, it will 70 be evident from an examination of Figures 12 and 14 that it may be slit to provide eight, ten or various other numbers of blades.

A packing structure of the general type 75 thus far described is fully illustrated and described in my copending application Serial Number 594,193, titled "Packing structure," to which reference may be had if desired.

In the present invention the several slits are closed throughout their length so as to 80 provide a packing structure having a maximum packing efficiency, especially under 85 heavy pressures.

The preferred method of making a packing structure of this nature having closed 90 slits, consists of longitudinally slitting a piece of material A, of suitable length, from one end inwardly and at circularly spaced 95 intervals as illustrated in Figures 2 and 3, to form a series of circularly spaced blades 13, which are sector shape in cross-section and have a cross-sectional area less than one-half that of the piece and with the slits defining 100 the chord of the sectors. The successive slits are alternately angled transversely so as to be disposed on opposite sides of the longitudinal axis of the piece and the several slits extend a considerable distance inwardly so as to provide relative long blades.

The next step in the method is illustrated 105 in Figures 5 and 6, and consists of closing the slits. This is preferably accomplished by swaging the blades 13 inwardly at the zone B near the base of the blades. When 110 the structure is constructed of relatively soft ductile material which is susceptible of swaging in a cold state, the swaging is accomplished without heating the piece, but when constructed of harder material, such as for instance steel, it is proposed to first locally heat each blade at the zone B and 115 swage said blade inwardly while hot.

Such swaging of the blades 13 closes the 115 slits throughout their length, as shown.

The piece is now to be bored and turned, and in accomplishing this it is preferable to first form the central bore. In preparation for this operation a clamp ring 20 (see Figures 7 and 8) having an internal diameter to closely fit the external diameter of the piece A, is slid on said piece and set screws 21 carried by said ring clamp the respective blades 13 so that the blades will be firmly held against displacement during the boring 125 operation. With the blades 13 so clamped in place, the piece is bored and finished on the inside, and in the particular form of structure shown, the lower end is turned and 130

the valve seat 10 formed, and the piece is undercut to form the opposed internal shoulders 15 and 16. The upper end of the piece, including the blades 13, is turned to provide a lip 23 having an outer tapered surface 24. It will be noted that the bore intersects the several slits so as to form the intermediate blades 13^a, with each of such intermediate blades positioned between two of the spaced blades 13. Thus there is formed a plurality of yielding blades with their cooperating longitudinal edges having a permanent sliding engagement upon each other, this providing a structure having a complete circular exterior packing surface and at the same time providing a structure capable of expanding or contracting.

The piece is now turned and finished on the outside and in preparation for this operation the ring 20 is removed and the piece is preferably mounted as illustrated in Figure 9. This particular mounting permits the piece to be readily chucked in a lathe for turning and consists of a center rod 25 having at one end a cone collar 26 against which the seat 10 of the piece engages and is centered, and having its opposite end threaded. Screwed upon such threaded end is a collar 27 which has a slightly tapered hub portion 28 and a tapered bead 29 surrounding said hub. This collar serves to clamp the several blades clamped rigidly together during the turning of the piece, the hub portion 28 being of a diameter to closely fit into the upper end of the bore when the slits are closed and the tapered bead 29 being of proper diameter so that the lip 23 of the piece engaging into the tapered throat 30 of the collar 27 will effect a rigid clamping together of the several blades.

The piece is now turned to gauge and otherwise finished on the outside as shown in Figures 9 and 10, after which the lip 23 may be turned off.

While the above described steps of the method are followed in the making of the structure from a solid piece of material, it will be readily understood that such a structure may be made of a piece of tubing or other piece of material which is normally hollow. In making the structure from a piece of tubing, the tubing will be slit as illustrated in Figure 4, after which the step of swaging inwardly the blades 13^c, as above described, is followed to close the slits 12^a. The tubular piece is then finished on the inside, if such finishing is required, and then turned to gauge, in the same manner as above described.

In Figures 11 and 12 there is illustrated a packing structure of the same general type as above described, and which combines opposed packing structures 11^b and 11^d for use as a pump, compressor, or engine piston.

In Figures 13 and 14 I have illustrated an engine piston of the general form usual in explosive engines, and in which is incorporated a packing structure of the general character herein referred to. In this adaptation of the packing structure, the tubular packing member 11^a is slit from its upper end as at 12^c and at circularly spaced intervals in the same general manner as the previously described structures, to form a series of yielding blades, in this instance there being ten blades. The bore of the member 11^a has a tapered portion 35 and a threaded portion 36, adapting said member to be screwed upon the piston shell 37 with the tapered portion engaging a correspondingly tapered surface of said piston shell to form a gas tight joint.

It is particularly emphasized that the feature of major importance is the provision of a packing structure of this character in which the several slits are closed throughout their length, and in the method of closing the slits and then machining the structure to gauge, and while the structures and method of making as herein illustrated and described are fully adapted to fulfill all of the objects primarily stated it is to be understood that the invention is not to be limited to the specific form of embodiment herein disclosed, for it is susceptible of embodiment in various other forms, all coming within the scope of the following claims.

I claim:

1. An expandible packing structure comprising a tubular member longitudinally slit from one end inwardly and at circularly spaced intervals to form a series of blades, the several slits being closed throughout their length and transversely angled, whereby each blade throughout its length has a permanent coengagement with the adjacent blades.

2. An expandible packing structure comprising a tubular member longitudinally slit from one end inwardly and at circularly spaced intervals to form a series of blades, the several slits being closed throughout their length and the successive slits being oppositely angled transversely, whereby each blade throughout its length has a permanent coengagement with the adjacent blades.

3. An expandible packing structure comprising a tubular member longitudinally slit from one end inwardly and at circularly spaced intervals to form a series of yielding blades, each alternate blade having opposite longitudinal edges transversely converging outwardly and the intermediate blades having opposite longitudinal edges transversely disposed to correspond to those of the adjacent blades, the several slits being closed throughout their length to maintain the blades in permanent coengagement.

4. An expansible packing structure comprising a tubular member longitudinally slit at circularly spaced intervals to form a series of yielding blades, the several slits being closed throughout their length and the coengaging longitudinal edges of the several blades being angled transversely whereby the several slits remain closed during the expanding or contracting movements of the structure.

5. In a method of forming a cylindrical expansible packing structure, the steps consisting of longitudinally slitting through the wall of a hollow piece of material from one end inwardly and at circularly spaced intervals in transverse planes out of registry with the axis of said structure to form a series of blades, closing the several slits to bring the blades into cooperative engagement, and subsequently turning the piece to gauge.

6. In a method of forming a cylindrical expansible packing structure, the steps consisting of longitudinally slitting through the wall of a hollow piece of material from one end inwardly and at circularly spaced intervals in transverse planes out of registry with the axis of said structure to form a series of blades, swaging the alternate blades at their bases to close the several slits, and subsequently turning the piece to gauge.

7. In a method of forming a cylindrical expansible packing structure, the steps consisting of longitudinally slitting through the wall of a hollow piece of material from one end inwardly and at circularly spaced intervals in transverse planes out of registry with the axis of said structure to form a series of blades, heating the piece at the base of the blades, swaging the piece while hot to close the several slits, and subsequently turning the piece to gauge.

8. In a method of forming a cylindrical expansible packing structure, the steps consisting of longitudinally slitting through the wall of a hollow piece of material from one end inwardly and at circularly spaced

intervals, with the successive slits oppositely angled transversely and forming a series of blades, closing the several slits, 50 and subsequently turning the piece to gauge.

9. In a method of forming a cylindrical expansible packing structure, the steps consisting of longitudinally slitting through the wall of a hollow piece of material from one end inwardly and at circularly spaced intervals, with the successive slits oppositely angled transversely and forming a series 55 of blades, heating the piece near the base of the blades, swaging the piece while hot 60 to close the several slits, and subsequently turning the piece to gauge.

10. In a method of forming a cylindrical expansible packing structure, the steps consisting of longitudinally slitting a piece of 65 tubing from one end inwardly and at circularly spaced intervals to form a series of blades, swaging the tube in the region of the base of the blades to close the several 70 slits and bring the several blades into cooperative engagement, and subsequently turning the tube to gauge.

11. In a method of forming a cylindrical expansible packing structure, the steps consisting of longitudinally slitting a piece of 75 tubing from one end inwardly and at circularly spaced intervals to form a series of blades, heating the tube near the base of the several blades, swaging the tube while 80 hot to close the several slits and bring the several blades into cooperative engagement, and subsequently turning the tube to gauge.

12. In a method of forming a cylindrical expansible packing structure, the steps consisting of longitudinally slitting the wall of 85 a tubular piece of material at circularly spaced intervals to form a series of sections, closing the several slits to bring the sections into cooperative engagement, and subsequently turning the piece to gauge.

Signed at Los Angeles, California this 3rd day of February 1923.

JOHN A. ZUBLIN.
